FUEL PUMP

Byron R. Pool, Harrisburg, Ill., assignor of one-half to Theodore Coleman, Mount Carmel, Ill.

Application January 15, 1940, Serial No. 313,961

13 Claims.

(Cl. 251—101)

This invention relates to fuel pumps for internal combustion engines, and more particularly to pumps for engines of the solid fuel injection type.

Such pumps usually include a housing containing a series of individual fuel pumps connected to separate cylinders of the engine. The fuel is placed under pressure in the separate pumps, and fed to the corresponding cylinders through valves designed to open at a predetermined pressure, the amount of fuel fed from each pump being governed by a by-pass which insures against the passage of fuel to the engine cylinder so long as it is open. This type of pump is disclosed in my application Serial No. 221,405, filed in the United States Patent Office on July 26, 1938, to which reference is made for its general method of operation.

In such types of pumps, a number of operating problems have arisen. For instance, there have been instances of the failure of the by-pass valve because of abrupt contraction or expansion of the valve elements when subjected to sudden fuel temperature changes. In some cases the changes in dimension have been to a degree sufficient to cause seizing and binding of the moving elements with consequent damage, or to cause undue leakage and improper operation of the engine.

Trouble has also been encountered in maintaining sufficiently tight seals under the relatively high pressures characteristic of such solid fuel injection engines, particularly when necessary to adjust the individual pumps to insure each delivering the proper amount of fuel to its cylinder relative to the other pumps.

In overcoming the aforesaid disadvantages, it is a major object of this invention to provide an improved fuel pump characterized by longer and more dependable service, and less tendency to leak.

A further object of this invention is to provide a fuel pump having a novel by-pass valve construction wherein continued proper performance of the pump is insured regardless of changes in fuel temperature.

Still a further object of this invention is the provision of novel sealing means for a pump of the type described, wherein more satisfactory sealing over longer periods of time is insured, and the individual pump assemblies can be more easily adjusted to adjust the relative deliveries of fuel to their respective cylinders.

Further objects and advantages of the present invention will appear from the following description and attached drawings, wherein.

Figure 1 is a side elevation, taken partly in section, of a fuel pump embodying the present invention, the pump shown being governor-controlled.

Fig. 2 is a view similar to the upper end of Figure 1 illustrating an embodiment of the invention in a manually controlled pump.

Fig. 3 is an exploded view, taken partly in section, of the by-pass valve assembly of Figure 1.

Figs. 4 to 7, inclusive, are side elevations of a by-pass valve of the present invention, the different views being taken around the valve at 90° intervals.

Figs. 4a and 5a are end elevations of the valve as viewed in Figs. 4 and 5, respectively.

Fig. 8 is an exploded view in section of a valve cage of the present invention with the gasket provided therefor.

Fig. 9 is a plan of the valve cage of Fig. 8.

Figs. 10 and 11 are plans of the shims preferably used to adjust the individual pump assemblies in the housing cylinders.

Fig. 12 is an exploded view of the spring-pressed valve controlling the feed flow to the cylinders.

Fig. 13 is a section of the assembled valve of Fig. 12.

With reference to Figure 1, a fuel pump base or housing is shown at 11. A shaft 12 arranged to be driven from the engine is mounted in the housing, and is connected, by means not shown, to drive a vertical shaft 13 in synchronism with the engine. A centrifugal governor (not shown in detail), the weights of which are shown at 14, is provided to control the discharge of fuel from the pump, a lever 15 being provided to adjust the governor. A tappet-enclosing ring 16 is provided above housing 11 within which revolves a cam plate secured to shaft 13.

The features thus far described have been described only so far as they are necessary to an understanding of the present invention. Reference is made to my copending application above identified for a description of the detailed structure of the pump mechanism contained within the housing and its manner of operation.

A fuel pump head, generally indicated at H, and preferably of one-piece construction, is provided atop ring 16 and is secured thereto by suitable fastening means. Head H includes a section 17 formed with accurately dimensioned and preferably polished bores 18 to receive fuel pump assemblies 19 for the several cylinders of the engine on which the pump is mounted. Each of the fuel pump assemblies includes a cylinder 21 fitted in a bore 18 and secured therein by suitable fastening means, as described in my copending application above identified.

The relative position of the cylinders in bores 18 is preferably determined by the use of shims inserted between the top of the housing and retainer flanges 108 adjacent the tops of the cylinders.

Each cylinder 21 has a central bore to receive a piston or plunger 22 normally urged down

against the cam plate by spring 23, the piston being operated in synchronism with the engine by a cam on the cam plate in the manner disclosed in my application above identified.

Housing 17 is bored at its center as shown to provide two circular recesses 24 and 25 of different diameters separated by a shoulder 26. The smaller recess 25 is provided with an annular groove 27 which is sealed by a sleeve 28 on the inner wall of recess 25 to form an annular fuel supply chamber 29 to which fuel is fed through a suitable connection 105, as shown in Figure 2. A passage 31 for each pump unit 19 is provided leading from chamber 29 to an aperture 32 in the cylinder wall to deliver fuel to the cylinder bore when plunger 22 is withdrawn. Passage 31 is preferably formed by drilling from the outside of head H, the passage thus formed outside the cylinder being sealed by a plug 31'. Aperture 32 is preferably formed both as a round aperture and as a slot to facilitate the entrance of fuel into the cylinder bore, as described in my copending application above identified.

The inner wall of recess 24 in housing 17 is provided with a series of passages 33 corresponding in number to passages 31, each leading to an aperture 34 in the side of each piston. Passages 33 are preferably drilled in a manner similar to passages 31, the outer ends of the passages being sealed by plugs 33'. When passage 33 is closed by means to be later described, and the fuel is placed under pressure in a cylinder 19 by the plunger therein, it will pass to the selected engine cylinder through a connection generally indicated at 35, which preferably includes spring-pressed valve assembly, shown in detail in Figs. 12 and 13, to prevent the passage of the fuel except at a predetermined pressure. When passage 33 is open, the fuel placed under pressure in the cylinder 19 will by-pass therethrough and will not go to the engine cylinder. Therefore, the by-pass with its controlling mechanism functions as means to control the amount of fuel fed to the engine cylinders.

As pump assemblies 19 are of relatively small size, and it is necessary to seal against relatively high pressures at points spaced along the cylinder wall, proper sealing thereof has become a serious problem. Because of the small sizes of the elements, the very small clearances, and the construction of the assemblies, it is impossible to use separate gaskets, or any like means, without machine work that is prohibitive in cost. Furthermore, where actual removable gaskets are used in connection with machined grooves, the position of the pump cylinder in the housing bore is predetermined and fixed. Under such conditions, the problem of equalizing the volume output of the several units is serious because there is no way of adjusting the position of the pump cylinders in their housing bores without disturbing the seals or requiring new gaskets or different methods of grooving.

This problem of sealing is solved by the present invention wherein relatively thin layers of metal are electroplated, or otherwise integrally secured upon the outer surface of each assembly 19 as at 36, the several gaskets thus formed being preferably separated by grooves 37 formed in the outer pump cylinder wall to provide a series of pressure stages and increase the efficiency of the seals. While the pressures in the cylinder and in passage 33 run from 1,000 to 15,000 lbs. per square inch depending on throttle setting engine speed and injector nozzle setup, the seal thus

provided serves to prevent leakage through the housing bore either in an upward direction to the atmosphere, or downwardly to the fuel inlet, which is at a considerably lower pressure. Escape of fuel downwardly from the fuel inlet 32 is prevented by the provision of an additional electroplated gasket 38.

While gaskets 36 and 38 have been described as plated on the pump cylinder, it is to be understood that they may be also plated on the interior of the housing bore 18 receiving the pump cylinder. In either case, satisfactory sealing is assured. Furthermore, because of the very thin and integral gaskets that are thus provided, assembly and disassembly of the pump units in the housing is facilitated.

The gaskets 36 formed by electroplating may be of a single metal, or of a suitable alloy. Copper is preferably employed on engines with high pressure injection and fuel having a very low sulphur content. Copper-lead alloys (with a high lead content) are preferably used with fuel of high sulphur content. Under some conditions, an alloy of nickel and silver is preferred.

With the sealing means described and the bores 18 of constant diameter, and preferably with polished surfaces, a perfect joint is formed between the plated portions of the pump plunger cylinders, so that the cylinders or pumping assemblies may be moved lengthwise in the bores without lessening the efficiency of the sealing means. Longitudinal adjustment of the pump assemblies can be quickly and accurately made by use of shims, as shown in Figs. 10 and 11. Fig. 10 illustrates a shim 107 of generally U-shape which may be fitted between the top surface of housing 17 and the bottom surface of the circular retainer flange 108 of each pump assembly. Because of its shape, shim 107 may be inserted or removed from between the plunger body retainer flange and the pump head assembly without removing the plunger body from the pump head. A shim of this type may be readily used with pumps such as shown in Fig. 12 of the copending application above identified.

Shim 109 of Fig. 11 is of the type preferably used to effect longitudinal adjustment of wing type flanged plunger bodies of the type shown in Figs. 15 and 32 of the copending application above identified, and are also designed so that they may be removed or replaced without removing the plunger body from the pump housing.

While it might be supposed that any shims employed between the retainer flanges and the housing should be circular so that they can function as sealing means, and that it would be impractical to use a U-shaped shim which leaves one side of the contact area open, the novel sealing means provided herein enables a U-shaped shim to be satisfactorily used, since the necessary sealing is adequately cared for by the electroplated gaskets, and the shim, or shims, are not required to perform any sealing function.

As shims of the type shown in Figs. 10 and 11 vary in thickness from 0.001" to 0.015", any desired adjustment of the plunger body or pump assembly can be made.

By moving the pump assemblies lengthwise in the pump head bores, changes in the closing time of the plunger body or cylinder inlet port by the pump piston can be effected. This provides a simple, inexpensive, and effective means for equalizing the volume output of each pumping unit.

To control the extent and time of opening of

passages 33, and consequently the fuel delivered to the engine cylinders per cycle, a by-pass valve assembly is provided including a valve cage 39 (Figure 8), which includes an upper flange 41 having apertured ears 42 to be fastened to the housing by a valve cover 43 (Figure 1), and suitable fastening means such as bolts 44.

The body of valve cage 46 is formed with a bore 45 which functions as a valve seat, the main body of the cage being formed with a short cylindrical outer wall 46 and a wall 47 of frusto-conical shape. Wall 47 leads to a shoulder 48 and to a cylindrical walled section 49. The section of the cage bounded by wall 47 is provided with passages 51 positioned to be in alignment with passages 33 when the pump is properly assembled.

The wall of section 49 is preferably thin because it is contacted by the skirt or solid portion of the rotary valve which is substantially non-resilient and not compressible. Because of the thin wall construction, any undue binding between the valve cage and the valve at this point which will cause excessive friction will, in turn, cause this part of the valve cage to heat and quickly expand, thereby preventing failure of the valve at this point.

It will be noted that passages 51 of valve cage 46 are reduced in area at their inner ends to form metered holes at the points they open into bore 45 of the valve cage. This reduces the effective pressure exerted by the fuel injection pump on its delivering stroke against the sealing portion of the rotary valve, thereby greatly reducing the force necessary to maintain a satisfactory seal at those points.

To insure against the leakage of fuel around the valve cage, a gasket 52 (Fig. 8) is provided. Gasket 52 has an inner surface 53 shaped to generally conform to the frusto-conical surface 47 of cage 39, and an outer surface 54 shaped to generally fit the walls of recess 24 (Fig. 1). Gasket 52 is formed with passages 55 positioned to connect passages 51 of cage 39 and passages 33 of housing 17. Gasket 52 is preferably of relatively soft metal, so that when cage 39 is secured within the housing, a fluid tight seal will be created around the by-pass passages 33 leading from the respective pump assemblies to the by-pass valve. In addition, gasket 52 functions to seal the interior of the housing with respect to the exterior.

Referring to Fig. 3, shaft 13 is provided with a splined lower end 56 arranged to be driven from shaft 12 through suitable mechanism (not shown). Shaft 13 is formed of two sections 57 and 58 of different diameters separated by a shoulder 59. A rotary valve 61, preferably machined or constructed from a solid piece of metal, preferably resilient in character, is generally tubular in shape with an inner flange 62 defining two shoulders 63 and 64. Valve 61 has metering and non-metering sections corresponding respectively to sections 58 and 57 of the shaft. Its metering section is of a size to be fitted over section 58 of shaft 13, the lower skirt or non-metering surface of the valve beneath shoulder 64 fitting over section 57 of shaft 13 and shoulder 64 engaging shoulder 59. A key 66 on shaft 13 is positioned to engage a key-slot 67 (Figs. 5 and 5a) in valve 61, so that the valve will rotate with the shaft.

A sleeve-like member 68 is provided to fit over section 58 of shaft 13 within valve 61 and above flange 62 to cooperate with a nut 69 to hold valve 61 in position. Member 68 is slightly longer than

5 the portion of valve 61 above flange 62, so that when the assembly is complete and nut 69 is screwed onto the threaded end of shaft 13, member 68 will be secured between nut 69 and shoulder 63, but nut 69 will be above the upper end of the valve, so that the valve is not compressed thereby. Preferably there is a substantial clearance between the inside bore of valve 61 and sleeve 68.

10 Valve 61 is formed on its outer surface with two lugs 73 and 74. When the valve is assembled in the valve cage and the cage assembled with the housing, lug 73 operates to control the opening and closing of passages 33 as valve 61 is rotated by shaft 13. By reason of the diagonal positioning of side 75 of lug 73, movement of shaft 13 in a vertical direction and corresponding movement of valve 61 varies the transverse area of lug 73 that passes over passages 33, and accordingly varies the amount of fuel fed by each pump assembly to the engine cylinder to which it is connected.

15 As before pointed out, expansion and contraction of the valve assembly has introduced serious difficulties in the operation of the engine. For instance, when the valve cage contracts, it may seize and bind the valve, and when it expands, it may cause undesirable leakage. To compensate for this variation in the ratio of expansion and contraction between the rotary valve and the valve cage the metering or fluid control section of the rotary valve is oversized, that is to say made slightly larger than the corresponding portion of the tubular valve seat within which it operates. Thus, in the arrangement shown, the diameter of the rotary valve between lugs 74 and 73 is greater than the diameter of bore 45 of the valve cage. As an example, if the bore 45 of the valve cage is $\frac{3}{4}$ " in diameter (0.750"), the diameter of the valve across lugs 74 and 73 would preferably be about 0.7515" or approximately one and one-half thousandth inches greater than the diameter of bore 45, making it necessary to slightly compress the rotary valve diametrically to assemble the two units, thereby causing the lugs 73 and 74 to be resiliently held against the inner surface of the bore of the valve cage.

20 The pressure or resilient character of the valve can be varied by changing the dimensions of, or entirely eliminating slots 71 and 72. Or the portions of the valve that would be removed to form the slots may be left in place but reduced in thickness to provide the necessary degree of resilience.

25 The portion of the valve beneath shoulder 64 and referred to as the skirt is preferably of a diameter to provide a running fit with bore 45, the fit being close enough to prevent fuel leakage between the skirt and the valve cage into the lower part of the pump housing.

30 With this type of construction, if a sudden change in the fuel temperature should cause the valve cage to expand abnormally, the spring-like or resilient character of the valve will cause it to follow up and maintain a satisfactory seal. Likewise, if a fuel temperature change should cause the valve cage to contract, the diameter of the valve across lugs 74 and 73 will be reduced a like amount, preventing failure of the valve due to scuffing, seizing and/or sticking, a condition that is characteristic of a rotary valve of the solid type. Thus the valve assembly can be said to be of a self-adjusting type.

35 As above stated, the lower portion of valve 61

is preferably of a size to closely fit bore 45 of the valve cage. To prevent tipping or canting of the valve by reason of the high pressure of the fuel to which the surface of lug 73 is subjected when closing passages 33, lug 74 is provided substantially diametrically opposite lug 73, so that the pressure effective against lug 73 is transmitted to the opposite side of the valve cage and valve 61 is prevented from canting or tipping.

Since lug 74 crosses passages 33 only at a time when the corresponding fuel pump assembly is inoperative because of the cam on the cam plate being at a different point, the lug 74 has no effect as regards the control of fuel.

Valve cover 43 is recessed at 76 to provide a chamber to receive the ends of shaft 13 and valve 61 when the shaft is moved upwardly to vary the delivery of fuel. To insure proper positioning of the valve cover and the valve cage, valve cover 43 is preferably formed with an annular flange 11 extending into a recess 78 in the top of the valve cage. Recesses 78 and 76 receive the fuel fed from passages 33 and discharge it through a passage 79 to a fuel reservoir, preferably the fuel supply tank which supplies chamber 29.

In operation of the fuel pump herein described, fuel is fed from a suitable source of supply to chamber 29 from which it passes to each of the fuel plunger pump assemblies 19 through passages 31 when the pistons or plungers 22 in the pumps are in retracted position. As each piston 22 is moved upwardly by the cam on the cam plate (not shown), the aperture 32 of the pump assembly will be closed, and the fuel in the pump placed under pressure. As shaft 13 and valve 31 rotate with the cam plate and lug 73 is approximately in the same angular position on valve 61 as the cam on the cam plate, lug 73 will be effective to seal the by-pass passages 33 of each pump assembly when the piston of that assembly is being moved upwardly. As long as passage 33 of the assembly is closed by lug 73 and the minimum discharge pressure is maintained in the pump cylinder, fuel will be discharged to the corresponding engine cylinder through connection 35. As soon as passage 33 is opened by lug 73 moving thereby, the pressure on the fuel in the pump cylinder will be released. Flow of fuel to the engine cylinder will cease because of closure of the pressure valve 35, and the remaining fuel will be by-passed through passage 33, recesses 78 and 76, and outlet 79, back to the fuel supply.

By reason of the shape of lug 73, the period during which each passage 33 is sealed by the lug for a single rotation of the valve can be varied by axial movement of shaft 13 and valve 61. Axial movement of shaft 13 in an upward direction is preferably limited by an adjustable stop 81 threaded into a threaded hole 82 in the valve cover, the position of the stop being locked as by a lock nut 83. A cover 84 is preferably spot-welded, or otherwise secured to the top of the valve cover to prevent unauthorized tampering with the valve stop.

Figure 2 illustrates the present invention as embodied in a manually operated governor. Where elements are shown corresponding to similar elements in Figure 1, like reference numerals have been employed.

In Figure 2, a shaft 85 of considerably greater length than shaft 13 is provided to support valve 61. A sleeve 86 corresponding to sleeve 68 of Figure 3 is provided to be secured by a nut 87 screwed on the end of shaft 85, sleeve 86 being of considerably greater length than sleeve 68.

Nut 87 supports a bearing washer 88 on its upper face. A bearing 89 is provided between washer 88 and a second bearing washer 91 secured in position by a second nut 92 preferably locked by a cotter pin 92a. Bearing 89 is secured to a yoke member 93 having trunnions 94 and a rear guiding lug 95 which slides in a slot in a guide 96. Lug 95 with guide 96 prevents rotation of yoke 93 when shaft 85 rotates.

Trunnions 94 are engaged by a fork 91 mounted on a shaft 98 which is mounted to rotate in a valve cover 99 and connected, in turn, to suitable operating means. Thus when shaft 98 is rotated, yoke 93 is moved either up or down to effect vertical movement of shaft 85 and vary the amount of fuel being fed to the engine cylinders.

Valve cage 46 is preferably secured in place by valve cover 99 having suitable fastening means 101, and a flange 102 of a size to fit recess 78 and insure proper assembly of the parts. Valve cover 99 is apertured at 103 to receive the fuel from the by-pass valve and is formed with a passage 104 to return the fuel to the fuel supply.

Fuel is preferably introduced into chamber 29 in the main housing through a passage 105 leading to the outside of the housing at a point between adjacent pump assemblies. The path of the fuel through the pump is indicated generally by the arrows shown.

Valve assembly or connection 35 in its preferred form as shown in Figures 12 and 13 includes a valve housing 111 having a valve seat 112 therein, a valve 113, a valve spring 114, and a combined valve spring support and connector 115. Gaskets 116, preferably of an alloy, are provided to insure against leakage. Valve 113 is preferably formed with a sealing surface 117 and a series of radiating wings 118 which contact the sides of the passage within the husing and insure proper alignment of the valve at all times with substantially no interference with the flow of fuel through the valve assembly. This construction provides a unitary assembly that can be assembled at the factory and easily replaced in the field. Likewise, the simplicity of the valve enables it to be readily dismantled and serviced in the field.

The assembly of this invention is particularly advantageous in that it is interchangeable with different types of fuel injection pumps, such, for instance, as those of the manual control type, or the governor control type.

It is to be understood that the invention may be embodied in specific forms other than that illustrated without departing from the principle or essential characteristics thereof. The embodiments shown are therefore to be considered as illustrative and not restrictive, the scope of the invention being defined by the appended claims rather than the foregoing description and drawings. All modifications and changes which come within the meaning and range of equivalency of the claims are therefore intended to be included therein.

I claim:

1. A valve for use with a fuel pumping and distributing unit comprising a valve cage having a valve seat therein and a series of passages leading from said valve seat, an expandable resilient rotary valve in said seat having a section of less diameter than said seat, a lug on said valve section to engage the openings of said passages and control fluid flow therethrough, and a second lug on said valve section diametrically opposite said

first lug to maintain said first lug in sealing relation with said passages.

2. A valve for use with a fuel pumping and distributing unit comprising a valve cage having a valve seat therein, a rotary valve in said cage having one section of a diameter slightly less than the diameter of said valve seat and a second section of a diameter normally greater than the diameter of said valve seat, said valve having portions of reduced strength in said second section to permit said valve to be compressed diametrically to permit assembly in said valve seat, said second section being arranged to function as the fluid control sealing portion of said valve.

3. A valve for use with a fuel pumping and distributing unit comprising a valve cage having a valve seat therein with a relatively thick-walled section and a relatively thin-walled section, a rotary valve in said cage having a valve supporting section of a diameter slightly less than the diameter of said valve seat and a fluid control sealing section of a diameter normally greater than the diameter of said valve seat, said valve having portions of reduced strength in said latter section to permit said valve to be compressed diametrically to permit assembly in said valve seat, said first valve section being arranged to rotate adjacent the thin-walled section of said cage.

4. A valve for use with a fuel pumping and distributing unit comprising; a valve cage having a valve seat with fluid openings therein to be controlled; and a rotary valve in said seat having a fluid control sealing section opposite said openings and of normally greater diameter than the adjacent portion of said valve seat, and a non-fluid control section at one end of said fluid control sealing section and of substantially rigid and non-resilient character and of a size to fit snugly in said valve seat.

5. The valve of claim 4 wherein said fluid control sealing section including: a metering lug disposed in the plane of said openings to open and close said openings on rotation of said valve; and a second lug diametrically opposite said metering lug to engage the adjacent portion of said valve seat and maintain the metering lug in sealing relation with the openings.

6. The valve of claim 4 wherein said fluid control sealing section is slotted, said slots terminating adjacent the boundary between said rigid, non-resilient section and said fluid sealing section.

7. A valve for use with a fuel pumping and distributing unit comprising: a valve cage having a cylindrical bore, the wall of which forms a valve seat; and a valve, rotatable within said seat, having rigidly joined metering and non-metering sections; the metering section being inherently resilient and of greater diameter, when removed from the seat, than the diameter of the seat, and being radially compressible to an extent sufficient to permit its insertion into the valve seat and to enable it when inserted to conform itself instantaneously to the expansions and contractions of the valve seat during operation; the non-metering section being substantially rigid and dimensioned to fit snugly within the seat, said non-metering section functioning as a valve sealing and guiding member.

8. A valve for use with a fuel pumping and distributing unit comprising: a valve cage having an open ended tubular bore, the wall of which forms a tubular seat; a valve actuating shaft in said bore spaced from said seat; an open ended tubu-

lar valve having rigidly joined metering and non-metering sections extending around said shaft within said bore, the metering section being spaced from the shaft, radially compressible and of a size slightly larger than the bore of the cage so that it normally is compressed by the seat; and means for securing the non-metering section of the valve to the shaft, the securing means being constructed and arranged to clear the metering section sufficiently to avoid interference with its normal radial expansion and contraction during operation.

9. The valve of claim 8 wherein the securing means comprises: a transverse internal flange on the non-metering section of the valve; a transverse shoulder on the shaft positioned to abut one side of the valve flange; and means adjustably connected to the shaft and arranged to engage the other side of the valve flange to clamp it against the shaft shoulder.

10. A valve for use with a fuel pumping and distributing unit comprising: a valve cage having an open ended tubular bore, the wall of which forms a tubular seat; a valve actuating shaft in said bore spaced from said seat, said shaft having free and drive end portions projecting respectively from opposite ends of said bore; an open ended tubular valve having rigidly joined metering and non-metering sections extending around said shaft within said bore, the metering section being spaced from the shaft, radially compressible and of a size slightly larger than the bore of the cage so that it normally is compressed by the seat; an internal annular flange on the non-metering section of said valve; an annular shoulder on the shaft abutting the drive side of the flange; a sleeve extending over the shaft within the metering section of the valve, the sleeve being of a size sufficiently smaller than the metering section to avoid interference with the normal expansion and contraction of that section during operation; and adjustable means on the projecting free end of the shaft, engaging the sleeve to clamp the valve flange between the sleeve and the shaft shoulder.

11. The valve of claim 10 wherein: the valve and the sleeve are insertable into and removable from their respective operating positions through that end of the assembled valve which corresponds to the free end of the shaft.

12. A valve for use with a fuel pumping and distributing unit comprising: a valve cage having a cylindrical bore, the wall of which forms a sealing seat; and a unitary valve, rotatable in said seat, having a fluid sealing and metering section of greater normal diameter than said seat and a fluid sealing and non-metering section of substantially the same diameter as said seat, said metering section being formed with pre-determined portions of reduced strength to enable said valve to be compressed diametrically for assembly in said valve seat.

13. A valve for use with a fuel pumping and distributing unit comprising: a valve cage having a cylindrical bore, the wall of which forms a valve seat; and a unitary valve, rotatable in said seat, having a fluid sealing and metering section of greater diameter than said seat and a fluid sealing and non-metering section of substantially the same diameter as said seat, said valve being slotted along the metering section only to enable such section to be compressed diametrically when inserting the valve within said seat.

BYRON R. POOL.
